WALL INSTALLABLE VACUUM CLEANER UNIT

James C. Hamrick, Matthews, N.C., assignor to Jet Line Products, Inc., Matthews, N.C., a corporation of North Carolina

Filed June 6, 1966, Ser. No. 2,560

Term of patent 14 years

(Cl. D9—2)

FIGURE 1 is a perspective view of the wall installable vacuum cleaner unit showing my new design;

FIGURE 2 is a front elevational view thereof on a smaller scale; and

FIGURE 3 is a side elevational view thereof also in smaller scale looking from the left side of FIGURE 1.

The dominant features of my design reside in those portions shown in full lines.

I claim:

The ornamental design for a wall installable vacuum cleaner unit, as shown and described.
